UNITED STATES PATENT OFFICE.

JAMES T. COWLEY, OF LOWELL, MASSACHUSETTS, ASSIGNOR TO THE LAMSON CONSOLIDATED STORE SERVICE COMPANY, OF NEWARK, NEW JERSEY.

CONVEYING APPARATUS.

SPECIFICATION forming part of Letters Patent No. 608,578, dated August 9, 1898.

Application filed November 10, 1896. Serial No. 611,585. (No model.)

To all whom it may concern:

Be it known that I, JAMES T. COWLEY, of Lowell, county of Middlesex, and State of Massachusetts, have invented certain new and useful Improvements in Conveying Apparatus, of which the following is a specification; and I hereby declare that the following is a full, clear, and exact description of the invention, which will enable others skilled in the art to which it appertains to make and use the same.

My invention relates to improvements in conveying apparatus, and especially to the class of conveying apparatus known as "cable carriers," and it has for its object to provide means on the several tracks converging at the terminal station whereby carriers belonging to a certain track can engage only the propelling-cable of said track when placed thereon at the terminal station and be propelled to the station to which they belong.

My invention consists of certain novel features hereinafter described, and particularly pointed out in the claims.

In the accompanying drawings, which illustrate a construction embodying my invention, Figures 1 and 2 represent, respectively, a plan and a side view of a line composed of an upper and a lower track entering the terminal station or cashier's desk. Fig. 3 is a detail perspective view showing the gripping mechanism on the carrier engaging with the cable. Fig. 4 is a detail plan view showing the means whereby a carrier on a track to which it does not belong is prevented from engaging the cable. Fig. 5 is a side view showing the carrier on the track with its gripping mechanism engaging the cable. Fig. 6 is an end view of the carrier. Fig. 7 is a plan view of the forwarding and return track at the terminal station or cashier's desk. Fig. 8 is a plan view of six lines entering the terminal station and showing the carriers placed on the tracks to which they belong to be propelled to the stations from which they came.

Like letters of reference refer to like parts throughout the several views.

The two opposite rails A' form the forwarding-track A and are supported and firmly se-

cured to the standard X. Near said standard X the rails are spread out of a straight line to form an opening A², at which point the carrier is applied to the forwarding-track A. The carrier D is adapted to engage with a cable C, running over pulleys E, mounted in the lugs E' on said standard X and connected to and driven by a suitable driving mechanism. The carrier D is provided with a cover D', held in a closed position by a suitable spring-catch which is adapted to be operated by a push-button D² to release the cover D', and the spring D³ will throw up the cover D' and open the interior of the carrier.

D⁴ represents suitable switching pins or lugs by which the carriers are switched at their respective stations. These lugs are placed in different positions on said carriers to correspond with switch-guides at different stations along the line, so that the carriers can be switched at the stations desired.

The lever D⁵ is provided with a pin D⁶, upon which the gripping-jaws D⁸ are pivotally mounted, and said lever D⁵ is journaled in suitable lugs D⁷ on the rear side of the carrier. These jaws D⁸ are each provided with a cam-slot D⁹, which works upon the stud D¹⁰, secured to the end of the carrier, and said cam-slots D⁹ are of such form that the jaws will be open as the lever D⁵ is lowered in position to cause the jaws D⁸ to engage with the cable C, as shown in dotted lines, Fig. 6. When the lever D⁵ is released, the spring D¹¹, located at the back of the carrier and around the lever D⁵ between the lugs D⁷, will operate to raise the lever D⁵ and close the jaws D⁸ upon the propelling-cable C. (Shown in Figs. 3 and 5.)

D¹² is a plate secured to the bottom of the carrier by screws D¹³, and said plate is provided with ears D¹⁴, which are adapted to pass under the rails A' of the track A and hold the carrier thereon, as said ears extend beyond the said rails A', excepting where said rails A' are bulged at A² to permit a carrier being placed on said rails.

D¹⁵ represent friction-rollers mounted on the screws D¹³ and free to revolve thereon, and the object of these rollers is to reduce the

90
95

friction caused by the carriers traveling along the track, around the corners, and into the stations.

The rails A' are secured to the bracket A³, located near the standard X, and to the upper end of said standard X there is secured a cam-plate A⁴, and to the lower end of said cam-plate there is secured a flat plate A⁵, provided with a transverse slot A⁶, from which there leads a longitudinal slot A⁷. From said plate A⁵ there extends a rod A⁸ for a purpose hereinafter described. As the carrier is placed on the forwarding-track by the cashier where the tracks are shown as bulged at A² and is pushed by hand, as is usual in all cable carriers, the end of the lever D⁵ passes under the cam-plate A⁴ and lower plate A⁵. Now as said carrier is pushed and said lever is pressed down by the cam-plate A⁴ the gripping-jaws D⁸ are opened to the position shown in Fig. 6, and when the pin F on the end of the lever D⁵ registers with the slot A⁷ the lever D⁵ and the pin F will pass up through the slots A⁶ and A⁷, and owing to the spring D¹¹ the gripping-jaws D⁸ will close upon the cable C, and the carrier will be propelled to the station to which it belongs. (See Fig. 3.) Now if a carrier belonging to another track was placed by mistake upon the track shown in Fig. 3 the pin F would not register with the slot A⁷, (see Fig. 4,) and consequently the lever D⁵ could not pass up through the slot A⁶; but upon the continued pushing by the cashier the lever D⁵ would pass under the rod A⁸, which may be of any desired length. The said lever D⁵ passing under said rod A⁸ would prevent the jaws D⁸ closing on the cable, and the carrier would remain in the position to which moved by the cashier, who, observing that the carrier did not grip the cable, would readily understand the difficulty and withdraw said carrier from said track and place it upon the track to which it belonged. The guide-rod A⁹ serves to steady the carrier as the lever D⁵ passes under the cam-plate A⁴. The carriers are sent into the cashier's station from the clerks' stations on the lower track B, composed of the opposite rails B', and said rails are bulged out at B² the same as track A at A² (see Figs. 1 and 7) in order to allow the carriers to be removed, because the distance between the rails B' where bulged is greater than the distance between the ears D¹¹ of the plate D¹². The rods B³, located on the opposite sides of the rods B', serve to keep the carriers on the return-track B as they pass into the terminal station. B⁴ represents a suitable bumper against which the carriers strike when coming in on the return-track, and B⁵ is a suitable brace connecting the rails B'.

Referring now to Fig. 8, it will be seen that the pins F and the slots A⁷ are differently located for each track running into the terminal station, and said pins and slots are so arranged that the pin F of the carriers belonging to a certain track will register only with

the slot A⁷ of the plate A⁵ of said track, so that the gripping mechanism on the carriers belonging to a certain track will engage only the cable of said track. It will be seen from said figure that the lever D⁵ and pin F of each carrier will register with the slots A⁶ and A⁷ of the track on which the carrier is placed upon reaching said slots, and upon said lever and pin passing upwardly through said slots the gripping-jaws D⁸ will close upon and grip the cable and the carrier will be propelled. It will also be seen that the lever D⁵ and pin F of each carrier will register only with the slots A⁶ and A⁷ of the track on which said carriers are shown placed in said Fig. 8. Consequently carriers belonging to a certain track will be propelled only to the station from which they came. 85

From the foregoing description it will be understood that although several cable-lines, each composed of an upper and a lower track and of the same general construction, enter one terminal station from various parts of the store yet by the mechanism above described, even though the carriers become mixed at the terminal station and are placed by the cashier on the return-track of the wrong line, the gripping mechanism of the carriers wrongly placed will not operate to engage the cable of and be propelled on the wrong track. Consequently the carriers running into a terminal station on the several lines can only be propelled on the tracks to which they belong for return to the clerks or salesmen from whom they came. 100

I do not limit myself to the arrangement and construction shown, as the same may be varied without departing from the spirit of my invention. 105

What I claim as new, and desire to secure by Letters Patent of the United States, is—

1. In a conveying apparatus, the combination of the tracks and propelling-cable with a terminal station into which said tracks enter, carriers adapted to travel on said tracks and each provided with a gripping mechanism for engaging the cable, and mechanism on each track at said terminal station for operating the gripping mechanism of the carriers to bring said gripping mechanism into position to grip the cable, mechanism for causing said gripping mechanism to grip the cable, the gripping mechanism of the carriers belonging to a certain track and the said grip-operating mechanism of said track being provided with registering parts whereby only carriers belonging to a certain track can grip the cable of said track and be propelled thereon. 115 120 125

2. In a conveying apparatus, the combination of the tracks and propelling-cable with a terminal station into which said tracks enter, carriers adapted to travel on said tracks and each provided with a gripping mechanism for engaging the cable, a lever connected to said gripping mechanism and adapted to operate the same, and a cam on each track at said terminal station for operating said lever to 130

operate the gripping mechanism of the carriers to bring said gripping mechanism into position to grip the cable, mechanism for causing said gripping mechanism to grip the cable, the said lever of the gripping mechanism on the carriers belonging to a certain track and the cam of said track being provided with registering parts whereby only carriers belonging to a certain track can grip the cable of said track and be propelled thereon.

3. In a conveying apparatus, the combination of the tracks and propelling-cable with a terminal station into which said tracks enter, carriers adapted to travel on said tracks and each provided with a gripping mechanism for engaging the cable, a lever connected to said gripping mechanism and adapted to operate the same and provided with a projecting pin, and a cam on each track at the said terminal station for operating said lever to actuate the gripping mechanism of the carriers to bring said gripping mechanism into position to grip the cable and provided with slots through which said actuating-lever and pin pass to cause the engagement of the gripping mechanism and cable, and a spring located on and acting on said lever to cause the gripping mechanism to grip the cable, the said lever and pin of the carriers belonging to a certain track being adapted to register with the slots of the cam of said track whereby only carriers belonging to a certain track can grip the cable of said track and be propelled thereon.

25 pass to cause the engagement of the gripping mechanism and cable, mechanism located on the carriers for causing said gripping mechanism to grip the cable, the said lever and pin on the carriers belonging to a certain track being adapted to register with the slots of the cam of said track whereby only carriers belonging to a certain track can grip the cable of said track and be propelled thereon.

4. In a conveying apparatus, the combination of the tracks and propelling-cable with a 35 terminal station into which said tracks enter, carriers adapted to travel on said tracks and each provided with a gripping mechanism for engaging the cable, a lever connected to said gripping mechanism and adapted to operate 40 the same and provided with a projecting pin, a cam on each track at the said terminal station for operating said lever to actuate the gripping mechanism of the carriers to bring said gripping mechanism into position to grip 45 the cable and provided with slots through which said actuating-lever and pin pass to cause the engagement of the gripping mechanism and cable, and a spring located on and acting on said lever to cause the gripping 50 mechanism to grip the cable, the said lever and pin of the carriers belonging to a certain track being adapted to register with the slots of the cam of said track whereby only carriers belonging to a certain track can grip 55 the cable of said track and be propelled thereon.

In testimony whereof I have signed my name to this specification, in the presence of two subscribing witnesses, on this 31st day 60 of October, A. D. 1896.

JAMES T. COWLEY.
